ATTORNEY

UNITED STATES PATENT OFFICE.

WALTER L. HUNTER, OF ROANOKE, TEXAS.

FRUIT-JAR AND BOTTLE CLEANER.

1,296,290.

Specification of Letters Patent.

Patented Mar. 4, 1919.

Application filed October 2, 1917. Serial No. 194,379.

To all whom it may concern:

Be it known that I, WALTER L. HUNTER, a citizen of the United States, residing at Roanoke, in the county of Denton and State of Texas, have invented certain new and useful Improvements in Fruit-Jar and Bottle Cleaners, of which the following is a specification.

My invention relates to devices used to 10 clean the interior of receptacles having small mouths and impossible to thoroughly clean by insertion of the hand into the receptacle, and are particularly of the type provided with a pair of handles to open and close the 15 jaws of the cleaner.

An important object of my invention is to provide a device of the character above mentioned, including means carried by the jaws for securing a cleaning element thereto.

Another object of my invention is to provide a device of the above mentioned character having its jaws so formed that the cleaning element secured thereto will be forced into close engagement with the 20 interior walls of the receptacle when the handles of the cleaner are brought toward each other.

A further object of my invention is to provide a device of the above mentioned 30 character, including novel jaw construction whereby all the crevices may be thoroughly cleaned.

Another object of my invention is to provide a device of the above mentioned character which is strong, durable, inexpensive to manufacture and efficient in practice.

Other objects and advantages of the invention will be apparent during the course of the following description.

In the accompanying drawings forming a 40 part of the description and wherein like numerals are employed to designate like parts throughout the same,

Figure 1 is a view of the device inserted in 45 a receptacle, and

Fig. 2 is a side elevation of the invention.

In the accompanying drawings wherein for the purpose of illustration is shown a preferred embodiment of my invention, the 50 numeral 1 designates a pair of handles pivoted together, each of which carries a perforation at their lowermost point. Pivoted to these handles by means of rivets 2 or the like, are a pair of jaws 3, which are further 55 connected together by a fulcrum link 4. This fulcrum link consists of a strip of metal

having its ends formed into loops to receive rivets passing through perforations in the jaws. These jaws diverge from this point a substantial distance, then diverge at a 60 smaller angle to form the portions 5, which are adapted to come into close proximity with the interior walls of a receptacle.

Ordinarily a cleaning element is secured to the jaws by means of cord or an elastic band, 65 but I provide a novel means for this purpose, which consists of reducing the lower ends of the jaws and bending them inwardly and upwardly to form hooks 6. On these jaws at a point adjacent the fulcrum link, I also provide hooks 7 which are preferably formed integral with the jaws and extend inwardly and downwardly. Cleaning elements 8 preferably rags, are adapted to have one end received on the hook 7, then wound spirally 75 down and around the jaws 3, around the hook 6, then the hook 6 passed through the opposite end of the rag. The numeral 9 indicates an ordinary fruit jar.

To use the invention, the rag is attached as 80 above stated and the handles are separated, which causes the lower ends thereof to become farther apart. The jaws 3 being pivoted to the handles and connected by the member 4, are brought together thereby allowing the cleaner to be inserted into a receptacle. The handles are then closed, which action forces the jaws apart and engages the cleaning element with the interior walls of the receptacle. The cleaner may be turned 90 around in the receptacle or the receptacle may be given a movement to clean the same. It will also be noted that the top crevice below the neck of the receptacle may be cleaned by spreading the jaws apart and inserting 95 one hooked end of the jaw and rubbing the same through the crevice.

It is to be understood that the form of my invention herewith shown and described is to be taken as a preferred example of the 100 same and that various changes in the shape, size and arrangement of parts may be resorted to without departing from the spirit of the invention or the scope of the subjoined claims.

Having described my invention, I claim:

1. A receptacle cleaner comprising a pair of handles pivotally connected, a pair of jaws pivotally secured to said handles, a fulcrum member pivotally connecting the two jaws 110 together, and a cleaning element adapted to be detachably secured to each of said jaws.

2. A receptacle cleaner comprising a pair of crossed handles pivotally connected together and having their ends extending beyond the pivot, a pair of jaws pivotally secured to said extended ends, a rivet carried by each of said jaws adjacent their connection with said handle, a fulcrum member having an eye formed upon each end thereof for pivotal engagement with said rivets and

for connecting the two jaws together, hooks 10 on said jaws and a cleaning element adapted to be detachably connected to said hooks.

In testimony whereof I affix my signature in presence of two witnesses.

WALTER L. HUNTER.
